EXTRACTOR APPARATUS

Edward R. Gould, Philadelphia, Pa.

Application June 22, 1934, Serial No. 731,811

6 Claims. (Cl. 210—76)

The present invention relates to laundry equipment and more particularly to an improvement in extractors.

Some of the objects of the present invention are to provide an improved extractor for more expeditiously removing liquid from clothes, fabrics or other materials; to provide a novel means for mounting the rotary basket or element of an extractor whereby stresses and strains are lessened and vibration reduced to a minimum; to provide a new and original sectional container for holding the material in an extractor; to provide an improved material container wherein provision is made for quickly dumping the contents of the container; to provide a material container which can be packed for shipment in a minimum space; to provide a container for an extractor wherein the construction allows for automatic expansion thereof when subjected to centrifugal force; and to provide other improvements as will hereinafter appear.

In the accompanying drawings Fig. 1 represents a perspective of an extractor embodying one form of the present invention and showing a novel material container in position for lowering into the extractor; Fig. 2 represents one unit of the container in assembled condition; Fig. 3 represents the same in knock-down form for shipment; Fig. 4 represents a section on line 4—4 of Fig. 2; Fig. 5 represents the unit of Fig. 2 in discharge position; Fig. 6 represents a sectional elevation of the extractor showing a modified form of container in elevation and partly lowered towards extracting position; and Fig. 7 represents a perspective of the container shown in Fig. 6.

Referring to the drawings one form of the present invention consists of a casing or "curb" 10, of open top cylindrical shape, which is supported in the usual manner upon spring hangers 11 from fixed stanchions 12 anchored to a suitable base. As here shown a truss-like frame 13 is riveted or otherwise made fast to the outside of the bottom 14 of the casing 10 and serves as a rigid mounting for a bearing 15 in which the vertical driving shaft 16 is stepped. This shaft 16 extends into the casing 10 and terminates in a face plate 17 to which the rotary basket 18 is made fast. Preferably an annular track 20 is mounted upon the inner face of the bottom 14 and the rotary basket 18 travels thereon through the medium of anti-friction rollers 21. The basket 18 is of the usual perforated construction having an open top for the reception, in this instance, of a novel form of material container, instead of receiving the material directly as in the ordinary practice.

In Figs. 1 to 5 inclusive a form of container embodying the present invention is shown consisting of two half units 22 arranged to be as-

sembled back to back for lowering into the extractor basket 18, but when so assembled being free to move relatively towards and away from each other. As these units are duplicates the present description will be confined to one and like parts in the other designated by like reference numbers.

The unit 22 is preferably formed of relatively heavy wire so interconnected and shaped as to form a rectangular frame 23 as a back, and upper 10 and lower substantially semi-circular top and bottom bars 24 and 25 projecting from the same side of the frame 23. These bars 24 and 25 are interconnected by vertically disposed rods 26, the ends of each of which are respectively 15 threaded for right and left hand screw action to enter correspondingly threaded socket eyes 27. As here shown there are five socket eyes 27 on the bar 24 and a like number on the bar 25, each opposite pair being joined by a rod 26 to 20 maintain the proper spacing between the bars 24 and 25, and to strengthen and reinforce the unit. The rear frame 23 as well as the curved front area of the unit is covered with wire mesh, or open-work cloth, or any other suitable material 28 capable of retaining the fabrics or goods to be centrifuged and permitting the water to pass therethrough for proper action.

In order to support the fabrics or goods in the unit, a liquid pervious bottom is provided 30 preferably consisting of a perforated metal plate 29 hinged to the bottom bar of frame 23 and conforming to the shape of the unit bottom, so as to form a complete closure therefor. A hook 32 or other fastening means is provided to engage the bar 25 and lock the bottom in place as a support for the contents of the unit.

Since the units are designed to be handled by modern overhead travelling lift mechanism, lift rods 33 are permanently attached respectively at one end to the lower corners of the frame 23 and incline towards the center of the top bar 24, where each is made fast by a clamp 34 to the aforesaid bar 24. Each of these secured rod ends terminates in an eye 35 projecting above the bar 45 24 in position to be easily engaged by hooks 36 of the lift mechanism 37. Thus the mechanism 37 can be removably connected to the two eyes 35, and also to an eye 38 at the middle of the bar 24 so that the hanging weight will be equally distributed and no undue strains placed upon the fabric or other mesh body cover. When so suspended on the carrier mechanism 37 the filled units can be transferred from one place to another and for emptying the hook 32 is released 50 from the bottom bar 25 whereupon the hinged bottom swings downwardly and allows the clothes, fabrics or other material to fall by gravity out of the unit. In connection with this dumping action attention is directed to the fact that while 60

the upper bar 24 of the top of the unit may be either of rigid material or flexible, it is preferable to employ a relatively heavy flexible cable so that the lifting effort of the mechanism 37 will tend to draw this flexible cable 24 inwardly toward the rear frame 23, as shown in Fig. 5. This performs a function not possible in the rigid type of construction because if any of the materials or fabrics in the unit tend to wedge or stick to the sides of the unit this drawing together of the top will press the material toward the open bottom and ensure prompt and complete discharge.

The form of material holding unit shown in Figs. 6 and 7 consists of two semi-circular container baskets each formed of an upper metal rim 40 and a lower metal rim 41 which are interconnected by vertical bars 42 and enclosed by a fabric cover conforming to the shape of the metal frame-work. Each half of this unit is open at the top but provided with a suitable bottom preferably fabric covered which is capable of being released for discharge purposes as will be understood. In assembling the two container parts the opposed flat surfaces are arranged in juxtaposed relation and the two upper semi-circular bars 40 are interconnected by means of pivoted links 45 and the lower semi-circular bars 41 are interconnected by links 46. The ends of these pairs of links are apertured to receive the respective hook ends of a rod 47 and the end of each of these rods terminates in a hook 48 by means of which the container can be engaged by the hoisting mechanism for lifting it out of and lowering it into the extractor basket 18. During the lifting movement the links 45 and 46 will collapse upwardly to draw the two halves of the container together so that it can be readily removed from or lowered into the basket 18, but when the container is located in the basket 18 and free of the lifting mechanism the centrifugal action causes the links to spread with an action somewhat similar to a toggle joint so that the two halves of the container move upwardly to seat flush against the inner wall of the basket 18. It will therefore be noted that in both forms of the units either that of Figs. 1 to 5, or Figs. 6 and 7 there is provision for the unit automatically expanding and seating tightly against the inner periphery of the basket 18. This relieves the unit parts of the ordinary strains received from a centrifugal action and yet the construction is such that units are automatically withdrawn radially as soon as the lifting mechanism starts to lift them axially. In each construction the normal diameter of these units is less than the inner diameter of the extractor basket 18 and consequently in either form the units can be readily lowered or lifted out of the basket without interference.

Another feature of the unit construction shown in Figs. 1 to 5 inclusive is the provision for compact shipment, in that the brace rods and support rods can be removed, the top and bottom folded flat against the rear frame, and the removable bars placed flat on the collapsed unit for easy packing purposes. At the destination the rods can readily be replaced and the entire assembly shaped for use in a relatively short time.

For driving the extractor basket 18 the shaft

10 in the present instance carries a pulley 50 driven by a belt 51 from a second pulley 52 associated with and driven by a motor 53.

While only two forms are shown in which this invention may be embodied, it is to be understood that the invention is not limited to any specific construction, but might be applied to various forms without departing from the spirit of the invention or the scope of the appended claims.

Having thus described my invention, I claim:— 10

1. In an extractor, a material container consisting of a frame-work forming a semi-cylindrical unit having an open bottom, said frame-work including detachable spacing bars, a bottom hinged to said frame-work, means to latch said bottom in closed position, and a cover of liquid pervious material for said frame-work and said bottom.

2. In an extractor, a material container consisting of a frame-work forming a partly cylindrical unit having an open bottom, said frame-work being formed of a rear frame, a top bar, and a bottom bar, threaded socket eyes carried by said bars, spacer rods threaded into top and bottom pairs of said eyes, a cover of liquid pervious material supported about said frame-work, and a hinged bottom for said unit.

3. In an extractor, a material container consisting of a frame-work forming a partly cylindrical unit having an open bottom, said frame-work being formed of a rear frame, a flexible top bar, and a bottom bar, threaded socket eyes carried by said bars, spacer rods threaded into top and bottom pairs of said eyes, a cover of liquid pervious material supported about said frame-work, and a hinged bottom for said unit.

4. In an extractor, the combination of a casing, a material container arranged to fit within said casing, said container consisting of a frame-work forming a partly-cylindrical unit having an open bottom, said frame-work including detachable spacing bars, a bottom hinged to said frame-work, means to latch said bottom in closed position, a cover of liquid pervious material for said frame-work and said bottom, and means to rotate said container with said casing.

5. In an extractor, the combination of a casing, a material container arranged to fit within said casing, said container consisting of a frame-work forming a partly-cylindrical unit having an open bottom, said frame-work including detachable spacing bars, a bottom hinged to said frame-work, means to latch said bottom in closed position, a cover of liquid pervious material for said frame-work and said bottom, and means including a perforated basket for rotating said container.

6. In an extractor, the combination of a casing, a material container arranged to fit within said casing, said container consisting of a frame-work forming a partly-cylindrical unit having an open bottom, said frame-work including detachable spacing bars, a bottom hinged to said frame-work, means to latch said bottom in closed position, a cover of liquid pervious material for said frame-work and said bottom, means including a perforated basket for rotating said container, and means between the bottom of said basket and the bottom of said casing to support said basket.

EDWARD R. GOULD.
